STATIONERY PACKAGE

Evelyn von Hartmann, Westwood, N. J., assignor
to Novelart Manufacturing Company, Long
Island City, N. Y., a firm

Application August 28, 1944, Serial No. 551,456

4 Claims. (Cl. 206—63)

1

This invention relates to stationery packages.

An object of this invention is to provide a stationery package including a holder in which is separately packed envelopes, writing paper and a blotter, the holder being so constructed that the envelope, blotter and paper are easily accessible and removable therefrom.

Another object of this invention is to provide an article of the character described comprising a folder having a pair of hinged sections receiving the writing paper therebetween, and a cover member associated with one of said pair of sections and provided with tabs extending through slits in said latter section, and forming therewith a compartment for envelopes, said tabs serving to retain a blotter on an inside surface of said section.

Yet another object of this invention is to provide in a stationery package of the character described, a folder having a section formed with a plurality of slits, and a section hinged to said first section and formed with side walls engaging said first section and with tabs on the side walls passing through said slits, whereby to space the first section from the second section to form a compartment therebetween to receive a plurality of envelopes, one end of said second section being adapted to be lifted to release one of the tabs from its slit, whereby to open said compartment and permit removal of envelopes therefrom.

Yet another object of this invention is to provide a neat, compact stationery package of the character described which shall be relatively inexpensive to manufacture, and yet practical, attractive and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown various possible illustrative embodiments of this invention:

Fig. 1 is a top plan view of a stationery package embodying the invention.

Fig. 2 is a top plan view of the package shown in Fig. 1 with the cover section unfolded and laid flat.

Fig. 3 is a top plan view of the folder with the hinged-together sections of the folder opened up.

Fig. 4 is a cross-sectional view taken on line 4—4 of Fig. 1.

2

Fig. 5 is a cross-sectional view taken on line 5—5 of Fig. 1.

Referring now in detail to the drawing, 10 designates a stationery package embodying the invention. The same comprises a folder 11 adapted to carry a plurality of envelopes 12, a blotter 13, and sheets of writing paper 14. The folder 11 comprises a pair of rectangular sections 16 and 17 preferably of the same size. Section 17 10 may be made of relatively stiff cardboard, whereas section 16 may be made of heavy paper or relatively thin cardboard. Sections 16 and 17 15 may be hinged together by a flexible hinge 18 which may comprise an elongated strip of tape or cloth or the like flexible material having side edges 16a and 17a pasted or otherwise secured to adjacent end edges of sections 16 and 17. Strip 18 preferably has an intermediate portion 19 between portions 16a and 17a to permit sections 20 16 and 17 to be spaced from one another.

The sheets 14 of writing paper are placed on section 17 and between sections 16 and 17.

Extending from section 16 is an integral member 20, formed from the same blank. The cover member 20 comprises a flat top wall or section 21 which may be of any decorative shape and which may be printed or embossed on its outer surface with any suitable picture or printed matter. Section 21 is connected to section 16 by a 25 side wall 22. Section 21 is preferably of less width and length than section 16 so as to only partially cover the latter. The length of wall 22 is less than the length of section 16. As shown in the drawing, side wall 22 terminates short of the 30 ends of section 16. The length of side wall 22 35 may be equal to the length of section 21.

Extending from the upper and lower ends of section 21 are end walls 24 and 25 of the same width as side wall 22, having edges 24a and 25a 40 of walls 24, 25 contacting section 16. Extending from walls 24 and 25 are tabs 28 and 29 of less length than walls 24 and 25 and formed at the inner ends thereof with tongues 28a and 29a.

It will be noted that side wall 22 is connected 45 to sections 16 and 21 by fold or crease lines 22a and 22b respectively. Walls 24 and 25 are connected to section 21 and tabs 28 and 29 by crease lines 21a and 21b, respectively.

At the end of section 21 is an end wall 32 parallel to wall 22 and connected to section 21 by 50 crease line 32a. The width of wall 32 is the same as the width of walls 22, 24 and 25. Extending from wall 32 is a tab 33 connected to wall 32 by crease line 32b. Wall 21 is formed with a tab 55 tension 21c cut from walls 32 and 33. Thus walls

32 and 33 are formed with a slit 34 to produce the tab 21c when wall 32 and tab 33 are bent downwardly from section 21. By reason of the slit 34 a cutout or opening is formed in wall 32 and tab 33 when said wall and tab are bent downwardly from section 21.

Section 16 is formed with a pair of parallel slits 40 and 41 aligned with walls 24 and 25 and with a slit 42 aligned with wall 32.

The cover section 21 may be folded over section 16 and tabs 28, 29 and 33 pass downwardly through slits 40, 41 and 42, respectively.

It will be noted that wall 32 is longer than tab 33 thus forming edges 44 on said wall adapted to contact section 16. It will be noted that walls 24, 25 and 32 form side walls of a compartment 50 when the tabs 24, 25 and 33 are passed through the slits 40, 41 and 42. Within the compartment 50 are the envelopes 12. To remove an envelope, it is merely necessary to grasp the tab 21c and pull out the tab 33, thus exposing one side of compartment 50 through which envelopes may be removed. It will be noted that tabs 28, 29 and 33 are folded inwardly after passing through the slits. The blotter 12 is slipped in beneath section 16 and engages tabs 28, 29 and 33 as illustrated in Fig. 3 of the drawing.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. A stationery package comprising a folder, said folder comprising a pair of sections hinged together at adjacent ends, one of said sections being formed with a plurality of slits, a cover member extending from one of said sections and folded thereover, and forming a compartment therewith, envelopes within said compartment, said cover member being provided with tabs which

extend through said slits, and lie parallel to the face of said slotted section and a blotter retained against the inner surface of said slotted section by said tabs.

5 2. A folder comprising a pair of superposed hinged-together sections, a cover member extending from one side of one of said sections, said cover member having side and end walls, and a top wall, said latter section being formed with slits, said end walls, and one of said side walls being formed with tabs extending through said slits, said top wall being formed with a tab extension cut from said one of said side walls, said tabs being folded inwardly, and a sheet held against the inner surface of said latter section by said inwardly folded tabs.

3. A folder comprising a pair of superposed hinged-together sections, a cover member extending from one side of one of said sections, said cover member having side and end walls, and a top wall, said latter section being formed with slits, said end walls, and one of said side walls being formed with tabs extending through said slits, said top wall being formed with a tab extension cut from said one of said side walls, said tabs being folded inwardly, and a sheet held against the inner surface of said latter section by said inwardly folded tabs, said cover forming a compartment with said latter section, and envelopes within said compartment.

4. A stationery package comprising a folder, said folder comprising a pair of sections hinged together at adjacent ends, one of said sections being formed with a plurality of slits, a cover member extending from said slotted section and folded thereover to form a compartment therewith, envelopes within said compartment, said cover member being provided with tabs which extend through said slits and lie parallel to the face of said slotted section, a blotter retained against the inner surface of said slotted section by said tabs, writing paper interposed between said pair of sections, and the other of said pair of sections being of relatively stiffer material than said slotted section, and a tongue on at least one of said tabs to engage an end of one of said slits.

EVELYN VON HARTMANN.
